UNITED STATES PATENT OFFICE

ALLAN CHENEY, OF MELROSE, MASSACHUSETTS

SEEPAGE PROTECTOR FOR MASONRY BUILDINGS

Application filed October 8, 1931. Serial No. 587,543.

This invention relates to a novel seepage protector for masonry buildings, and aims to provide a protector which shall prevent water seeping through a masonry wall from finding its way into and through a roof. The protector may be employed in connection with parapets or walls, and for similar purposes.

The invention will best be understood by reference to the following description, when taken in connection with the accompanying drawing of certain specific embodiments thereof, while its scope will be pointed out more particularly in the appended claims.

In the drawing:

15 Fig. 1 is a vertical, sectional view of a portion of a masonry building having a seepage protector embodying the invention;

Fig. 2 is a perspective view of one form of the seepage protector;

20 Fig. 3 is a sectional view, on an enlarged scale, of the preferred wall siding or facing forming a part of the protector;

Fig. 4 is a sectional view, on an enlarged scale, on line 4—4 of Fig. 3;

25 Fig. 5 is a perspective view of a modification of the protector;

Fig. 6 is a vertical, sectional view, of another modification of the protector; and

30 Fig. 7 is a vertical, sectional view of still another modification of the protector.

Referring to the drawing, and to the embodiments of the invention illustrated therein, and having reference at first to Fig. 1, there is shown by way of example a portion 35 of a masonry building comprising a molded, concrete roof 10, and a parapet, the latter as shown comprising courses of brick 11, a facing 12 and a coping 13, united as is customary by mortar 14. Adjacent to the parapet, the roof has an oblique portion 15 of common form. Overlying the roof and its oblique portion, and extending part way up the inner side of the parapet, is a usual sheathing, commonly composed of several layers of material 40 16, such as tarred paper, asphalt paper or pre-

pared roofing, mopped with any bituminous material as it is applied. Sometimes these roof sheathings are built of alternate layers of felt and asphalt, or felt and coal tar pitch, or felt and plastic cement.

To prevent moisture which enters the coping from seeping downwardly through the parapet and into and through the roof, I have provided a novel seepage protector comprising a flashing strip 17 of sheet metal such as copper, and a siding or facing 18, of suitable sheet material, which may be and herein is woven cotton drilling 19, saturated with asphalt 20, and having coatings 21 of asphalt on both sides. This material is preferred, because, while thoroughly waterproof and durable, it is flexible, and when applied, can be overlapped with the roof sheathing in some such manner as that illustrated in Fig. 1, and will flex and accommodate itself to the irregularities of the surfaces to which it is applied. It is not only overlapped to a considerable extent with the roof sheathing, but, as herein shown, is carried down the oblique portion to the horizontal portion, and as it is being applied, is thoroughly mopped with bituminous material, to make a watertight joint.

The sliding 18 is suitably secured to the flashing 17, as by providing the latter with a downwardly-directed flange 22, folded to present a re-entrant portion 23, presenting a groove or channel 24, which receives a correspondingly folded margin of the siding 18, the two parts being tightly squeezed together and clenched to form a strong and waterproof seam. As shown in the form illustrated in Figs. 1 and 2, this seam is especially strong and effective, because the flashing which is employed is similar to that illustrated in U. S. Letters Patent No. 1,728,955, issued September 24, 1929, to The Cheney Company, as my assignee.

This flashing comprises a strip of sheet metal, such as copper, folded to present

grooves 25 and ridges 26, alternately arranged on both sides of the strip. The grooves and ridges are formed with side walls 27 common to both grooves and ridges, 5 and inclined to both faces of the sheathing to form dovetail grooves and ridges. The side walls taper longitudinally of the grooves and ridges. As stated in the said patent, the 10 flashing, when embedded in the mortar, provides a perfect mechanical bond in every direction between the flashing and the adjacent course of masonry. The bending of the flashing to form the flange 22 flattens the ridges, so that the side walls are pressed 15 against the bottoms of the grooves, thereby forming plaits 28, best shown in Fig. 4 which not only reinforce and stiffen the flange, but also serve to pinch the compressible siding 18 in the manner shown in Fig. 4, and to 20 hold the siding much more securely than would be possible with a plain, flat flashing.

This effect can also be secured in the form illustrated in Fig. 5, by providing the flashing with a shallow, saw-tooth formation, 25 presenting sloping ridges 29 and inclined walls 30, so that when the flashing is bent to form a flange 31, as in the case of the form shown in Fig. 2, the ridges, when flattened, present plaits 32, which squeeze 30 and pinch the siding in a manner similar to that which is shown in Fig. 4.

In case a plain, flat flashing 33 is employed, as in the form shown in Fig. 6, additional strength is imparted to the seam by a double-clenched joint, formed by a flange 34 bent inwardly as at 35, then upwardly as at 36, then outwardly as at 37, and then downwardly as at 38. Also in Fig. 7, there is shown a plain, flat flashing 39, having a 40 downwardly-directed flange 40, to which the siding is secured as by rivets 41. However, the form illustrated in Figs. 1 to 4, inclusive, is preferred, because not only is the seam strengthened by the plaits, but the interlocking of the flashing in all directions with the mortar avoids breaking of the bond, when subjected to stress in any direction. In all forms of the invention, however, the protector can be manufactured as a merchantable article, to be supplied to the builder and installed with ease and rapidity. The depth of the siding will depend upon the situation in which it is to be used, and in all cases will be great enough to overlap the 55 roof sheathing, and to provide a perfectly safe and durable, waterproof construction.

Having thus described certain embodiments of the invention, but without limiting myself thereto, what I claim and desire by 60 Letters Patent to secure is:

1. In a seepage protector for masonry walls and the like, the combination of a continuous sheet metal flashing extending through said wall from side to side for embedding horizontally in a layer of mortar,

and a flexible side for overlying a vertical portion of said wall and a portion of the roof, and means connecting said siding to said flashing.

2. In a seepage protector for masonry walls and the like, the combination of a continuous sheet metal flashing extending through said wall from side to side for embedding horizontally in a layer of mortar, 70 and a flexible side for overlying a vertical portion of said wall and a portion of the roof, 75 said flashing and said siding being clinched together continuously throughout their lengths.

3. In a seepage protector for masonry walls and the like, a metal flashing sheet of desired width to extend through said wall from side to side and formed with means adapted for interlocking engagement with the mortar of said wall, and formed with a portion extending beyond the side of said wall, and a flexible fabric base flashing connected to said flashing sheet continuously along one edge thereof, said flexible flashing being entirely on the outside of said wall 90 when applied thereto.

4. A seepage protector for masonry walls and the like as in claim 3 wherein the extending edge of the flashing sheet and flexible flashing are interlocked together as by folding the flashing in reverse bends.

5. A seepage protector for masonry buildings and the like according to claim 3 wherein the sheet metal flashing is provided with a downwardly extending longitudinal flange 100 provided with inwardly extending reentrant portions terminating in a groove, for interlocking engagement with the flexible flashing whereby said flexible flashing will lie snugly against the side of said wall.

6. In a seepage protector for masonry walls and the like, the combination of a continuous metal flashing sheet of substantial width to extend through said wall, said sheet being formed with transversely extending ribbed portions providing grooves and ridges for the reception of mortar or the like to bond said sheet securely in said wall and prevent relative lateral and vertical movement of the masonry courses above and below said sheet, one longitudinal edge of said sheet providing a downwardly and inwardly extending portion providing a reentrant groove, and a flexible fabric waterproofed covering locking engaged in said groove and adapted to closely fit and overlie the side of said wall and adjacent roof joint.

7. A seepage protector for masonry buildings and the like according to claim 6 wherein the ribbed portions of said sheet are flattened across the reentrant groove providing spaced unyielding thickened portions for compressing the fabric and securely locking said fabric to said flashing sheet.

8. In a building construction, the com- 130

bination of a masonry wall comprising superposed courses of masonry with layers of mortar therebetween, a roof, and a roof covering therefor, a metal flashing sheet extending through said wall and formed with means for the reception of mortar to bond the courses of masonry above and below said sheet securely together against relative lateral and vertical movement, and a flexible fabric waterproof sheet connected to said flashing along one longitudinal edge and extending downwardly along the face of said wall and overlying the roof joint and adapted to be cementitiously connected thereto.

15. 9. In a building construction, the combination of a masonry wall composed of superposed courses of masonry held together by intervening beds of mortar, a roof, and a roof covering therefor, means for preventing seepage downwardly through said wall and roof joint therewith, comprising a metal sheet extending through said wall from side to side, and having permanent bonded connection with said courses of masonry, and a flexible waterproof sheet connected to said metal sheet and overlying the side of said wall and adjacent roof joint and adapted to be cementitiously connected with said roof covering, whereby a continuous seepage protector is provided from the outside of one wall to the outside of the opposite wall of said building.

10. A seepage protector for masonry buildings and the like containing a wall composed of superposed courses of masonry and a roof, of means for preventing the infiltration of moisture downwardly through said wall or at the roof joint therewith comprising an impervious metal flashing sheet embedded in said wall and bonded thereto and extending entirely therethrough, for preventing the infiltration of moisture downwardly through said wall, and a flexible fabric waterproofed sheet permanently connected to said flashing sheet, adapted to overlie the vertical side of said wall and adjacent portion of said roof and conform snugly to the irregularities thereof, a covering for said roof of roofing material, said flexible sheet overlapping the outer edges of said roof covering and adapted to be cementitiously connected thereto.

11. A nailless, solderless and moisture-proof flashing for masonry buildings having a wall composed of superposed courses of masonry, a roof and a covering of roofing material for said roof, said flashing comprising a continuous sheet metal flashing of imperforate flashing sheets, extending through said wall from side to side and formed with means for the reception of mortar to bond the adjacent courses of masonry above and below said sheet together, a flexible waterproof sheet connected to said flashing sheet along one longitudinal edge and adapted to

overlie the vertical side of said wall and the adjacent portion of the roof covering and be cementitiously connected thereto, whereby to provide means for preventing seepage into the building extending continuously from the outside of said wall inwardly beyond the outer edge of said roofing and securely held in place without nailing.

In testimony whereof, I have signed my name to this specification.
